UNITED STATES PATENT OFFICE.

CHARLES W. NOKES, OF CLEVELAND, OHIO, ASSIGNOR OF ONE-HALF TO
EDWIN A. BONFIELD, OF SAVANNAH, GEORGIA.

DESIGN FOR A GAS-BURNER TIP.

SPECIFICATION forming part of Design No. 33,221, dated September 18, 1900.

Application filed June 9, 1900. Serial No. 19,780. Term of patent 7 years.

To all whom it may concern:

Be it known that I, CHARLES W. NOKES, a citizen of the United States, residing at Cleveland, in the county of Cuyahoga and State of Ohio, have invented and produced a new and original Design for Gas-Burner Tips, of which the following is a specification, reference being had to the accompanying drawings, forming part thereof.

In the accompanying drawings, Figure 1 is a plan view of my new design in gas-burner tips. Fig. 2 is a side elevation, and Fig. 3 is an elevation at right angles to Fig. 2.

The leading or material feature of my design, as shown, is in its appearance as a whole, and especially of its top part, including the burner-points 2. These are distinct upward projections oppositely out of the relatively-

large circular head 3, on which they occupy a small portion of the entire top area and are separated by a deep channel 8, traversing the full width of head 3. Each point 2 has a flat inclined surface 5 on its inner side, relieved by a bore 4, and a tubular shank 9, of much less size in cross-section than head 3, furnishes the bottom of said head.

What I claim is—

The design for a gas-burner tip, substantially as shown and described.

Witness my hand to the foregoing specification this 18th day of May, 1900.

CHARLES W. NOKES.

Witnesses:

H. E. MUDRA,
R. B. MOSER.
